UNITED STATES PATENT OFFICE.

MYERS C. CONWELL, OF LARCHMONT, NEW YORK, ASSIGNOR TO LAURA E. CONWELL
OF LARCHMONT, NEW YORK.

ANTIFREEZING ATTACHMENT FOR EXPLOSIVE-ENGINE-COOLING SYSTEMS.

1,253,789.

Specification of Letters Patent. Patented Jan. 15, 1918.

Application filed April 9, 1917. Serial No. 160,801.

To all whom it may concern:

Be it known that I, MYERS C. CONWELL, a citizen of the United States, residing at Larchmont, in the county of Westchester 5 and State of New York, have invented new and useful Improvements in Antifreezing Attachments for Explosive-Engine-Cooling Systems, of which the following is a specification.

10 This invention is an improved means for heating the circulating or cooling fluid in an explosive engine and radiator.

One of the objects of the invention is to provide means whereby the cooling fluid is 15 maintained at a temperature above the freezing point, and caused to circulate through the water jacket of the engine and the radiator. A further object is to provide an improved heating device capable of being attached to the explosive engine circulating 20 systems now in general use, without requiring alteration thereof. A further object is to provide an electrical heating device for the circulating system, which is capable of 25 being connected up with the lighting system of a motor vehicle, or with any other source of electrical energy.

The invention will be hereinafter fully set forth and particularly pointed out in the 30 claim.

In the accompanying drawing:—

Figure 1 is a diagrammatic view illustrating the circulating system of an automobile engine, with the invention applied thereto. 35 Fig. 2 is an enlarged detail view illustrating the heating device in longitudinal section.

Referring to the drawing, 10 designates the explosive engine or motor of an automobile, 11 the water jacket thereof, and 12 40 the radiator. A piece of flexible hose 13 communicates with the interior of the water jacket 11, and a similar piece of hose 14, communicates with the radiator 12.

The heating device comprises a metal tube 45 or spool 15, open at both ends, which ends are inserted into the free ends of the respective pieces of hose 13 and 14, whereby the latter are connected, and a conduit between the radiator and the water jacket is 50 provided. Said spool is provided with

spaced apart immovable annular flanges 16, spaced from the ends of the tube, whereby said ends form nipples capable of entering the ends of hose 13 and 14. A coil of resistance wire 17 is wrapped around the spool, 55 between the flanges, filling the space between the flanges to a thickness approximating the diameter of the flanges. Said resistance wire is provided with terminals 17^a, connected with a plug 18, of any desired construction, 60 capable of engaging a socket connected with the lighting system of the vehicle, and located at any point which may be found convenient, or it may be attached to a socket connected with the lighting system of the 65 garage. A sheet of non-conducting material 19 surrounding coil 17, prevents radiation of heat therefrom.

In practice, when the engine is not in operation, and it is desired to prevent freezing of the circulating fluid, the plug 18 is attached to the lighting system or to the lighting system of the garage, as may be desired. As the current passes through the wire 17, 70 the spool 15 becomes heated, thereby raising the temperature of the water within the connection between the radiator and the water jacket. Just as soon as the water commences to rise in temperature a circulation of the water in the cooling system is set up, and 75 said circulation is maintained as long as the current is passing through the heating coil. In this manner the temperature of the fluid is maintained above the freezing point throughout the entire system, thereby preventing damage to the latter, which might otherwise occur if the temperature of the 80 water should be allowed to fall in freezing weather.

Having thus explained the nature of the 90 invention, and described an operative manner of constructing and using the same, although without attempting to set forth all of the forms in which it may be made, or all of the forms of its use, the following is 95 claimed:—

An anti-freezing attachment for explosive engine cooling systems consisting solely of the following elements, a tube of uniform thickness and diameter throughout and 100

open at both ends, said tube being provided with two spaced apart stationary annular flanges, said flanges being also spaced from the ends of the tube, whereby said ends serve 5 as nipples to enter the ends of contiguous tubing, a coil of resistance wire encircling said tube between said flanges, the diameter

of the coil being approximately equal to the diameter of the flanges, and means whereby said resistance may be connected with a 10 source of electrical energy.

In testimony whereof I have hereunto set my hand.

MYERS C. CONWELL.
